UNITED STATES PATENT OFFICE

2,556,911

WATER HEATER FOR GAS RANGES

Albert R. Franklin, San Antonio, Tex., assignor
of one-half to Johnnie R. Franklin, San Antonio, Tex.

Application September 30, 1947, Serial No. 776,943

3 Claims. (Cl. 122—233)

1

This invention appertains to novel and useful improvements in a combination device for both cooking and heating and maintaining a supply of heated water.

An object of this invention is to heat a supply of water, retain the heated supply at a selected temperature, automatically increase the temperature of the supply of water when necessary to maintain a constant predetermined temperature, to maintain the ignition means in an operative manner and to supply means for conventionally heating pot and pans and the like.

Another object of this invention is to provide improved storage means for retaining water or other liquid therein, having fire walls extending therefrom for the purpose of receiving a burner therebetween.

Another purpose of this invention is to provide improved vent means associated with said burner means, said vent means being provided in a housing, wherein the above-mentioned apparatus is maintained.

Another purpose of this invention is to provide fluid flow control means associated with a pilot light, said fluid flow control means being actuated upon thermal response of the lighted pilot valve.

Another purpose of this invention is to provide a combination gas range accompanied by a water heater, all provided in one compact unit which may be positioned conventionally in a kitchen or the like.

Ancillary objects and features of novelty will become apparent to those skilled in the art, in following the description of the preferred embodiment of the present invention, illustrated in the accompanying drawings, wherein:

Figure 1 is a perspective view of the preferred form of the present invention;

Figure 2 is a longitudinal sectional view of a portion of the invention disclosed in Figure 3 and taken on the line 2—2 thereof and in the direction of the arrows;

Figure 3 is a transverse sectional view of the invention shown in Figure 2 and taken substantially on the line 3—3 thereof and in the direction of the arrows;

Figure 4 is a perspective view of the tank or receptacle including combination support members and fire walls; and,

Figure 5 is a plan view of a burner utilized in conjunction with the present invention.

Referring now in detail to the illustrated preferred embodiment of the present invention, like reference characters are used throughout to indicate similar elements.

2

This invention has been conceived and developed to provide a combination gas range and water heater, whereby space and expense may be saved by utility thereof. A substantially conventional gas range including all the pertinent features of the said conventional gas range is modified by the addition of a receptacle or tank for receiving and retaining a supply of water therein. Also associated with this receptacle or tank is means for retaining the water therein at a predetermined temperature. This means consists primarily of a particularly meritorious arrangement of valves, conduits, and thermostats.

The housing forming a major portion of the conventional gas range is modified to an extent so as to accommodate the water heater and retaining means. A selected compartment receives the receptacle therein and also receives the means for heating and automatically conditioning water in order that it may be maintained at a predetermined temperature. Vents are provided in this housing for the obvious purpose of supplying a flow of air in the required positions, adjacent the heating element or burner.

Forming a major portion of the present invention is the particularly meritorious receptacle or tank wherein water is stored. It will be noted as a pair of tanks juxtaposed and intercommunicated. Extending from the lower portion of a selected tank is a pair of fire walls which serve the purpose of supporting the said receptacle or tank. Immediately between these fire walls there is supplied a conventional burner for the obvious purpose of heating the liquid contained in the said tank. Of course, the area between the fire walls is intercommunicated with the zone which communicates with the vents mentioned above.

All of the appurtenances contiguous to a gas range (or if desired an electrically actuated range) are supplied in conjunction with the present invention. The usual burners are provided on the inside of the said housing and communicate with grates on the cover of the housing. Obviously, this construction permits cooking, heating and the like. Conventional broiler area as well as oven area is provided along with the conventional storage space or compartment in the said housing.

With the above as a background, reference is made primarily to Figures 1 and 2, wherein there is disclosed a housing 10, substantially conventional in nature. The said housing may be made of any suitable material such as porcelain covered metal or the like. A storage compartment 12 is provided in the said housing adjacent a broiler

compartment 14 and a conventional oven 16. Immediately adjacent the broiler compartment and oven is another compartment 18 wherein the major portion of the invention resides.

Seated in the said compartment 18 is the receptacle or tank disclosed in Figure 4. It will be noted that a first cylinder 20 is juxtaposed relative to a second cylinder 22 and these cylinders are intercommunicated. Obviously, this forms a single tank or receptacle for receiving water and the like therein. Support members 24 and 26 respectively extend from the lower receptacle 22 and form fire walls, whose function will be described later.

It will be noted that apertures 28 and 30 are supplied in the tanks or cylinders 20 and 22 respectively. The aperture 28 has a conduit 32 communicating therewith for the purpose of conducting heated liquid from the said tank.

Going to Figure 2, it will be noted that a conduit 34 extends through the housing 10 and protrudes in the said cylinder 22. It will be also noted that insulating walls 36 surround the said tank means for the obvious purpose of preventing undesired heat flow influence by radiation and convection.

Means for maintaining the liquid in the said tank at a predetermined temperature is provided. This means consists primarily of a conduit 38 which leads from a suitable supply of gas, either natural or butane or any other conventional admixture utilized for heating purposes. Provided in the conduit 38 is a valve 40 which is conventional in nature. This valve may be of any suitable type well-known in many arts. A thermo-couple 42 extends from the said valve 40 and terminates between the said fire walls 24 and 26 respectively. Also extending from the said valve 40 is another manually operated needle valve 44 which has a conduit or pipe 46 extending therefrom. This pipe 46 terminates in a pilot light nozzle 48 also between the said fire walls 24 and 26 respectively. It will be noted from an inspection of Figure 2 that the said thermo-couple 42 terminates adjacent the pilot light nozzle 48. The function of the said thermo-couple is to regulate the thermostatic valve 40. It is quite obvious that when a predetermined low temperature is attained in the thermo-couple 42, the thermostatic valve 40 is permitted to remain open thereby allowing gas or the like to flow to the burner 56. The valve 40 does not control the flow of fluid into the conduit 46, therefore, the pilot light will remain in the ignited condition regardless of whether the valve 40 is open or closed.

Of course, when the pilot light means is to be closed permanently, the manually operable valve 44 may easily be actuated to a selected position.

Also interposed in the line or conduit 38 is another thermostatic valve 50 having a rod (of the expansion type) 52 extending within the lower cylinder 22. At a predetermined temperature of liquid within the said tank, the rod 52 will contract thereby permitting gas to flow through the thermostatic valve 50. When the liquid within the tank reaches the maximum temperature (desired temperature), the rod 52 will expand to such a position as to close the said thermostatic valve 50.

The conduit 38 continues through a manually operable valve 54, thence to a detachable burner 56. The attachment of the burner to the said conduit 38 at this point is purely conventional, commonly known in the burner art.

The said burner extends between the fire walls 24 and 26 respectively and is in close proximity to

the pilot nozzle 48 and terminal portion of the thermo-couple 42.

A zone or area immediately behind the receptacle or tank is provided for the purpose of conducting flue gasses from between the said fire walls. A vent may be provided in the floor of the said zone and a chimney 58 may be provided on the upper portion of the said housing. It is noted at this point that the said conduit or pipe 34 may have an economizer therein, interposed within the chimney or flue zone. This economizer may be conventional in nature such as a simple coil of pipe or the like. However, the heat extracted from the flue gasses which would normally be exhausted through the atmosphere may be utilized and put to advantage thereby increasing the efficiency of the apparatus. A partition 60 is provided in the upper portion of the said compartment 18 thereby defining another zone wherein a burner 62 resides. A plurality of apertures 64 are provided in the cover of the said receptacle 10 and grates 66 may be positioned therein. Obviously, these apertures communicate with the zone immediately above the said partition 60 thereby lending access to the heat generated by burning the said burner 62.

A second set of apertures 68 and 70 respectively may be provided at the opposite end of the said housing 10 for the same purpose as the apertures 64. Of course, grates may also be placed over these last mentioned apertures 68 and 70 respectively. It is also within the purview of the present invention to supply another burner 62 beneath these apertures 68 and 70. Inspecting Figure 2, it will be noted that there are two apertures provided in the upper portion of the housing 10 constituting distinct and separate burning means. It will also be noted that only two other apertures constituting burning means are supplied adjacent but spaced from these apertures 64 and 66. Now, it is within the purview of the present invention to supply any number of burners in the housing. This is considered but a matter of design within the prerogative of the manufacturer.

It will be further noted that a sheet of insulation 72 may be supplied between the compartments 14, 16 and compartment 18. This insulation may be of conventional material such as rock wool, asbestos and the like. Also, suitable, conventional controls 74 may be supplied for regulating the flame in the burners 62.

While there has been described and illustrated but a single preferred embodiment of the present invention, it is apparent that various changes including omissions and additions may be made herein without departing from the spirit of the invention. Accordingly, limitation is sought only in accordance with the scope of the following claims.

Having described the invention what is claimed as new is:

1. A water tank sufficiently small to fit into a compartment of a stove and comprising two intersecting cylinders of equal diameters, permanently fixed together with their axes horizontal and parallel and in a vertical plane, the two cylinders communicating solely through the plane of intersection, and a pair of spaced parallel vertical side walls secured against the outer periphery of the lowermost cylinder and constituting the sole support means for the tank said side walls being disposed longitudinally of said cylinders and extending throughout the length of said cylinders.
2. In a heating appliance, a water tank com-

posed of two intersecting cylinders of equal diameters, permanently fixed together with their axes horizontal and parallel and in a vertical plane, the two cylinders communicating through the plane of intersection, means attached to one end of the lower cylinder for admitting fluid to the lower cylinder, means attached to the end of the uppermost cylinder remote from the first means for delivering fluid from the upper cylinder, and a pair of spaced parallel fire walls secured directly to the lower cylinder and constituting the sole means for supporting the tank in an elevated position, said fire walls being disposed longitudinally of said cylinders and extending throughout the length of the cylinders.

3. In a heating appliance, a water tank composed of two intersecting cylinders of equal diameters, permanently fixed together with their axes horizontal and parallel and in a vertical plane, the two cylinders communicating solely through the plane of intersection, insulating walls surrounding the cylinders, said cylinders each having a forward end wall and a rear end wall, means attached to the rear end wall of the lower cylinder for admitting fluid to the lower cylinder, means attached to the forward end wall of the upper cylinder for delivering fluid from the upper cylinder, and a pair of spaced parallel fire walls depending from the lower cylinder and extending throughout the length of the lower cylinder, said

5 parallel walls constituting the sole means for supporting the tank in an elevated position.

ALBERT R. FRANKLIN.
